UNITED STATES PATENT OFFICE

JOHN W. THOMPSON, OF PHILADELPHIA, PENNSYLVANIA, ASSIGNOR TO JOHN WANA-MAKER PHILADELPHIA, OF PHILADELPHIA, PENNSYLVANIA, A CORPORATION OF PENNSYLVANIA

DESIGN FOR A DISPLAY CASE

Application filed September 28, 1931. Serial No. 41,252. Term of patent 14 years.

To all whom it may concern:

Be it known that I, JOHN W. THOMPSON, a citizen of the United States, residing in Philadelphia, Pennsylvania, have invented a new, original, and ornamental Design for a Display Case, of which the following is a specification, reference being had to the accompanying drawings, forming part thereof, in which:—

Fig. 2 is a fragmentary detail perspective view of Fig. 1, partly in section.

I claim:—
The ornamental design for a display case, substantially as shown.

JOHN W. THOMPSON.
